FOREIGN PATENT DOCUMENTS

JP D15328456 S 9/2015

Primary Examiner — Paula Allen Greene(74) *Attorney, Agent, or Firm* — Michael Best and Friedrich LLP(57) **CLAIM**

The ornamental design for a headphone, as shown and described.

DESCRIPTION

FIG. 1 is a front, top, right perspective view of a first embodiment of a headphone showing my new design; FIG. 2 is a front, bottom, right perspective view thereof; FIG. 3 is a front elevational view thereof; FIG. 4 is a right side elevational view thereof; and FIG. 5 is a bottom plan view thereof.

FIG. 6 is rear, bottom, right perspective view of a second embodiment of a headphone showing my new design; FIG. 7 is a front, bottom, right perspective view thereof; FIG. 8 is a front elevational view thereof; FIG. 9 is a right side elevational view thereof; and, FIG. 10 is a bottom plan view thereof.

The broken lines showing the headphone portions are unclaimed portions thereof and form no part of the claimed design. The dot-dash broken lines showing boundaries of the claimed design and form no part of the claimed design.

1 Claim, 10 Drawing Sheets# US D854,511 S
